C. L. Parker,

UNITED STATES PATENT OFFICE.

FREDERICK C. HEMMER, OF BRADFORD, PENNSYLVANIA, ASSIGNOR TO STERLING VACUUM CLEANER COMPANY, OF BRADFORD, PENNSYLVANIA, A CORPORATION OF WEST VIRGINIA.

DUST-COLLECTOR.

948,993.

Specification of Letters Patent. Patented Feb. 15, 1910.

Application filed August 5, 1909. Serial No. 511,378.

To all whom it may concern:

Be it known that I, FREDERICK C. HEMMER, a citizen of the United States, residing at Bradford, in the county of McKean and State of Pennsylvania, have invented certain new and useful Improvements in Dust-Collectors, of which the following is a specification.

My invention relates to dust collectors and 10 more especially to dust collectors in use with a vacuum cleaner.

An object of my invention is to provide a dust collector which may be installed in connection with a vacuum cleaner without 15 materially altering the same.

A further object of my invention is to provide a dust collector, of a simple and durable construction, and so made that the parts of the same may be readily separated and assembled.

My invention consists generally of an outer receptacle within which is arranged a sack like strainer adapted to contain a smaller apertured receptacle, said outer receptacle having an inlet and outlet pipe.

In the accompanying drawings, forming a part of this specification, and in which like numerals designate like parts throughout the same, Figure 1 is a perspective view of my 30 dust collector showing the same as applied to a vacuum cleaner. Fig. 2 is a vertical longitudinal sectional view of Fig. 1, parts thereof being removed. Fig. 3 is a perspective view of the smaller receptacle of my 35 dust collector. Fig. 4 is a perspective view of the strainer.

In the drawings, 1 designates a flat board or the like, forming the bottom of a vacuum cleaner. Upon the bottom 1 is mounted the 40 driving mechanism casing 2 by means of the supporting member 3. A supporting brace 4 connects the driving mechanism casing 2 with a vacuum pump 5, which is operated by a train of gears within the casing 2, the pit 45 man 6 being connected to one of the gears and to the piston rod 7 of the pump 5.

8 designates the cylindrical outer receptacle of the dust collector having the outwardly projecting base 9, and a centrally arranged reduced portion 10, forming the shoulder 11 within the same. The upper edge of the outer receptacle 8 is bent outwardly to form the flange 12, upon which rests the outwardly projecting flange 13 of

the cover 14. The cover 14 is further provided with a downwardly projecting circular portion 15, adapted to fit within the upper end of the receptacle 8 and to form an air-tight connection therewith. A handle 16 is arranged upon the outer surface of 55 the cover 14, whereby the cover may be readily removed. Within the outer receptacle 8 there is arranged a sack like strainer 17, comprising a ring 18 upon which is secured the body portion 19 of the strainer, 60 which I preferably construct of a textile fabric having sufficient thickness and strength, although I may employ any suitable material. As shown in Fig. 2, the ring 18 rests upon the shoulder 11, of the outer 65 receptacle 8, and the strainer is supported thereby. Within the sack-like strainer 17, there is arranged the cylindrical cup-shaped receptacle 20 having the closed lower end 21 and the open, upper, outwardly flanged 70 end 22 below and near which are arranged the spaced apertures 23 upon the receptacle 20. As shown in Fig. 2, the smaller receptacle 20 is arranged within the sack-like strainer 17 and has its flanged upper edge 75 22 resting upon the ring 18, which in turn rests upon the shoulder 11 as hereinabove described. Above the receptacle 20, the receptacle 8 is provided with an inlet pipe 25, and it is further provided below the same 80 and near its bottom 9, with the discharge pipe 26. The pipes 25 and 26 have secured thereon, the pipes or hose 27 and 28 respectively, the hose 27 being provided at its end with a suitable nozzle (not shown) for application to the carpet or other article being cleaned, while the pipe 28 communicates with the pump 5 as shown at 29.

In the use of my strainer, a vacuum is created in the outer receptacle 8, by the 95 operation of the vacuum pump 5, having a connection with the receptacle 8 through the hose 28. The air charged with dust is then forced into the casing 8 through the inlet pipe 25 and travels downwardly in 100 receptacle 20 until it engages the lower portion of the same. The larger particles contained in the air strike against the lower portion of the receptacle 20 and are collected within the same. The smaller particles which remain within the air, are drawn up and through the apertures 23 105 upon the receptacle 20, into the sack-like

strainer 17 and are collected within the same, as the air passes through it, to the vacuum pump.

From the foregoing operation, it will be 5 obvious that the receptacle 20 serves as a protector for the strainer 22, the pressure and the greater part of the dust being taken up by said receptacle 20 and the strainer being freed from unnecessary strains which 10 might distort or tear it.

Having fully described my invention, I claim:

A dust collector of the character described, comprising an outer receptacle, provided with an inlet and outlet pipe, near the upper and lower ends thereof respectively, said outer receptacle having the lower end thereof closed and a detachable cover adapted to close the upper end thereof, said outer receptacle being further provided with an 15 20

inwardly projecting shoulder near the upper end thereof, a sack-like strainer comprising a ring and a body portion secured to said ring, arranged within said outer receptacle and having said ring supported by said inwardly projecting shoulder, a smaller receptacle having a closed lower end and an open outwardly flanged upper end, arranged within said sack-like strainer, said outwardly flanged upper end being arranged 25 30 upon said ring of said sack like strainer, and said smaller receptacle being provided with a plurality of apertures near the open end thereof, substantially as described.

In testimony whereof I affix my signature in presence of two witnesses.

FREDERICK C. HEMMER.
